UNITED STATES PATENT OFFICE.

JOSEPH HORACE POPE, OF BROCKTON, MASSACHUSETTS, ASSIGNOR TO THE AMERICAN HEELING MACHINE COMPANY, OF MAINE.

HEEL-NAILING MACHINE.

SPECIFICATION forming part of Letters Patent No. 399,777, dated March 19, 1889.

Application filed November 7, 1888. Serial No. 290,178. (No model.)

To all whom it may concern:

Be it known that I, JOSEPH HORACE POPE, a citizen of the United States, and a resident of Brockton, in the county of Plymouth and State of Massachusetts, have invented new and useful Improvements in Spanking and Slugging Devices, of which the following, taken in connection with the accompanying drawings, is a specification.

10 This invention relates to an improved spanking and slugging device for heelings-machines for boots and shoes, and it is carried out as follows, reference being had to the accompanying drawings, wherein—

15 Figure 1 represents a plan view of the device, shown in combination with a pair of heel and top-lift clamps, and Fig. 2 represents a side elevation of the same. Fig. 3 represents a detail plan view of the perforated spanker-plate, showing, partly in section, its connection to the handle by which it is operated. Fig. 20 4 represents a longitudinal section on the line A B, shown in Fig. 3; and Fig. 5 represents a cross-section on the line C D, shown in Fig. 1.

Similar letters refer to similar parts wherever they occur on the different parts of the drawings.

25 a in Figs. 1 and 2 represents the up-and-down movable plunger-rod of a heelings-machine of the kind shown in the patent granted to Tyler and Merritt, June 30, 1885, No. 321,401; and b represents the stationary sleeve in which said plunger-rod is guided, as usual.

c represents a hub or sleeve secured to and surrounding the sleeve b, which hub serves as a support for the heel and top-lift block d.

30 e e are the expansive heel-clamps pivoted in their rear ends, at e' e', to a block, e'', preferably made adjustable on pins e³ e³, secured to the block d, and made adjustable to and from the latter by means of the thumb-screw e⁴.

45 e⁵ is a yielding spring connecting the heel-clamps e e, as usual.

f f are the top-lift clamps arranged at a right angle to the above-mentioned heel-clamps; and the said top-lift clamps are constructed precisely like the heel-clamps, and,

like the latter, are pivoted at f' f' to a block, f'', adapted to slide on pin f³ f³, secured to the block d and made adjustable thereon by means of a thumb-screw, f⁴, screwed into the block d, as shown in Fig. 1.

55 f⁵ is a yielding spring connecting the top-lift clamps, as usual. I wish to state that the construction and arrangement of the said heel and top-lift clamps does not form the subject-matter of my present application, as the same is fully shown, claimed, and described in a separate application for a heelings-machine filed by me.

g is a rod secured to the hub d, and to said rod is clamped, by means of the set-screw h', 60 the handle h, as shown in the drawings.

In one piece with the handle h is made the grooved cross-bar h'', in which is adjustably secured the dovetailed carrier h³. Above the said carrier h³ is located the spanker-plate 70 holder h⁴, which latter is pivoted to the carrier h³ in one end by means of the screw-bolt h⁵, secured to the carrier h³, said bolt projecting through a perforation in the holder h⁴, and adapted to be adjustably secured to the 75 carrier h³ by means of a nut, h⁶, as shown in Figs. 1, 2, 3, and 4.

To the opposite end of the blade-holder h⁴ is secured the downwardly-projecting screw-bolt i, passing loosely through a perforation 80 in the carrier h³, and a slotted or forked opening, h⁷, in the cross-bar h'', as shown in Fig. 5 and in dotted lines in Fig. 3, said screw-bolt being provided with a fastening-nut, i', as shown in Figs. 2 and 5, by means of which 85 the holder h⁴ and carrier h³ are secured to the cross-bar h'' after the said parts have been adjusted relatively to said part h''.

In a slit in the holders h⁴ is inserted the metal spanker and slugger plate H, which is 90 pivoted to a pin, H', secured to the holder h⁴ in one end, and by means of a detachable pin, H'', passing through perforation in the holder h⁴ and plate H, as shown in Figs. 1, 2, 3, and 5.

95 The plate H may be easily detached from the holder h⁴ whenever so desired simply by removing the pin H'' and drawing the said plate out from the slit in the said holder.

The plate H is solid, with the exception of 100

the semicircular, or nearly so, shaped perforation K near its inner end, and elongated, preferably inclined, perforations k k near its outer end, as shown in Figs. 1 and 3.

5 The invention is adapted for use on a heel-ing-machine of the kind shown in the United States Letters Patent No. 321,401, granted June 30, 1885, to Tyler and Merritt, and the heel to be nailed is centered between the expansive heel-clamps e e, after which the heel is forced against the under side of the perforated nail-die, as usual, and after being perforated by the awls the nails are driven through the heel and sole in the usual manner, leaving the nail-heads projecting a little above the top of the heel. The jack is then moved away from the heel-clamps, a top lift in the meantime having been placed between the top-lift clamps f f. The operator takes 10 hold of the handle h and swings the said top-lift clamps to the position previously occupied by the heel-clamps. The previously-nailed heel is then moved to its original position below the nail-die and forced upward, causing the projecting upper ends of the nails to be forced into the under side of the top lift and the latter spanked onto the ends of the nails by the interposition of the solid portion of the spanker-plate H between the 15 nail-die and that portion of the top lift where the fastening-nails were previously driven. The slugs or "sight-nails" may afterward be driven into the heel through the perforation K and one or both of the perforations k in

the spanker-plate H without the need of taking off the pressure on the heel or the removal of the spanker-plate. 35

What I wish to secure by Letters Patent, and claim, is—

1. In a heel-ing-machine, the expansive 40 clamps f f, and the hub d, with its handle h, combined with the plate H, having the front and rear perforations, K k k, as and for the purpose set forth.

2. In a heel-ing-machine, the perforated 45 spanker and slugger plate H and the holder h⁴, secured together, as described, in combination with the handle h, the carrier h³, laterally adjustable in guides in said handle and pivoted to the holder, and having means, substantially as described, for securing the said carrier and holder in an adjustable manner to the said handle, as and for the purpose set forth. 50

3. In a heel-ing-machine, the hub d, having 55 the expansive clamps f f, and the rod g, secured to said hub, combined with the detachable handle h and the perforated spanker-plate H, secured to said handle in an adjustable manner, as and for the purpose set forth. 60

In testimony whereof I have signed my name to this specification, in the presence of two subscribing witnesses, on this 2d day of January, A. D. 1889.

JOSEPH HORACE POPE.
